OUTDOOR ADVERTISING SIGN OR SIMILAR ARTICLE

Conrad J. Escalante, 1251 W. Gaylord St.,
Los Alamitos, Calif.

Filed Nov. 19, 1963, Ser. No. 77,501

Term of patent 14 years

(Cl. D1—12)

FIG. 1.

FIG. 2.

FIG. 3.

FIG. 4.

FIGURE 1 is a front perspective view of an outdoor advertising sign or similar article embodying my new design;

FIG. 2 is a top plan view thereof;

FIG. 3 is an end elevational view thereof; and

FIG. 4 is a rear elevational view thereof.

I claim:

The ornamental design for outdoor advertising sign or similar article, substantially as shown.
